CIRCUIT INTERRUPTER

James M. Wallace, North Braddock, Pa., assignor
to Westinghouse Electric & Manufacturing
Company, East Pittsburgh, Pa., a corporation
of Pennsylvania

Application August 3, 1938, Serial No. 222,815

8 Claims. (Cl. 200—117)

This invention relates to circuit interrupters, and more particularly, to fuse devices of the type embodying a spring biased contact member normally held in closed circuit position by a fusible element and adapted, upon fusion of this element, to draw an arc into an arc-extinguishing chamber.

In the patent to H. H. Fahnoe, No. 2,095,736, issued October 12, 1937, is shown and described a fuse structure of the aforesaid type in which a spring-biased contact rod is held in current-conducting relation within this arc-extinguishing bore of a fuse tube by a pair of fusible connections, one of which is of low resistance and includes two leaf or strap members secured together by a low melting point solder, and the other connection is of higher resistance and serves as a strain member to relieve the soldered fusible joint of stresses due to the action of the biasing means tending to move the contact rod through the arc-extinguishing tube.

In order to provide a positive fuse operation upon the occurrence of a predetermined over-load, it is essential that the strap members separate at the fusible joint so as to divert the current through the high resistance strain member which, due to its lower current-carrying capacity, fuses in a relatively short interval of time, thereby permitting the spring biasing means to draw the contact rod through the arc passage to establish an arc therein. As set forth in the aforesaid patent, positive separation of the strap elements upon fusion of the soldered joint therebetween is obtained by constructing either of these elements, or both, of bimetal and arranging the elements with respect to each other, so that when heated by the load current, the two elements deflect away from each other.

The requiring biasing force to cause positive element separation may, in accordance with the above patent, also be obtained by making the strap elements or at least one of them, of spring material, which places a predetermined bias upon the elements tending to cause separation.

I have discovered that by constructing the strap elements of ordinary conducting material and arranging them in conjunction with the strain member so that the latter causes the spring biased contact rod to exert a small but constant lateral biasing force tending to move the elements apart, materially improved results may be obtained since the fusible solder joint between the strap elements is free from excessive mechanical strain which may under certain conditions occur in the bimetal construction to cause breaking of the joint and a false fuse operation. In accordance with my invention, the biasing force tending to separate the strap elements upon fusion of the fusible joint, is constant in that the biasing force is not dependent upon spring means that are re-

quired to carry current and which may, due to the heating effect of the current, lose their tension after long periods of use.

It is an object of my invention to provide a fuse device having a fusible element which is more reliable in operation than devices heretofore known in the art.

A further object of my invention is the provision of an improved fusible element for fuse structures which is capable of being calibrated to within closer limits than structures of the prior art.

Another object of my invention is the provision of a fusible element for fuse device, the structural arrangement of which permits the use of a wide range of fusible materials whereby better control of the blowing characteristics of the fuse devices may be obtained.

A more specific object of the invention resides in the provision of a fuse device of the type in which spring means are employed to move a conductor lengthwise within a tube for drawing an arc therein upon the release of the conductor by two successively fusible connectors, the one first to fuse consisting of two main current-carrying members joined by a fusible metal, and the one last to fuse serving as a strain element which is disposed out of alignment with the spring-biased conductor so as to produce a small but constant lateral biasing force for causing the two current-carrying members to separate upon fusion of the fusible metal.

Other objects and advantages relate to details of the fuse structure and will appear more fully in the following description when read in connection with the accompanying drawing, in which:

Figure 1 is a side elevation view partially in section and with certain portions broken away of an expulsion fuse embodying my invention;

Fig. 2 is a central longitudinal sectional view of the refill unit of the fuse structure shown in Fig. 1;

Fig. 3 is a perspective view of the fusible connections between the movable and the stationary terminal elements of my fuse device; and

Fig. 4 is a sectional view of the lower portion of the refill unit shown in Fig. 2, showing the relative position of the fusible connections following the first stage of the circuit interrupting operation.

In Figure 1 of the drawing, the reference number 6 designates a tubular member of insulating material, such as fibre, having a threaded portion at each end thereof for the reception of upper and lower metallic cap members 7 and 8, respectively. Between the cap members 7 and 8 is disposed a suitable weather-proof casing 11 of porcelain or the like. Disposed within the lower part 60 of the tubular member 6 is a fuse refill unit 13,

more clearly shown in section in Fig. 2. The fuse refill unit 13 comprises a tubular casing 15 of insulating material, such as fibre, having a metallic ferrule member 17 screw threaded to the lower end thereof. The ferrule 17 is provided with an inwardly projecting flange 19 upon which an insulating cylinder 21 is disposed.

Resting upon the cylinder 21 of insulating material is a tubular lining member 23, preferably formed of compressed boric acid or other suitable gas evolving substance. The tubular lining member 23 is held in position within the casing 15 by means of a plug 25 of insulating material screw threaded into the upper end of the casing. Disposed within the bore of the tubular lining member 23 is a metallic contact rod 27, the lower end of which terminates slightly above the lower end of the lining member 23 and is provided with two connecting conductors 29 and 31. These connecting members are more clearly shown in Fig. 3 and are adapted to be connected at their upper end to the contact rod 27 and are preferably disposed in a slot 33 provided in the end of the rod 27 and secured thereto by solder and a rivet 35. The lower ends of the connectors 29 and 31 are secured by means of a screw 37 to the ferrule 17.

The connecting conductor 29 comprises two strap-like members 39 and 41 of conducting and relatively stiff material, such as copper or bronze. The member 39 is substantially straight and forms an extension to the contact rod 27, whereas the member 41 is angular in shape, as shown, having a portion 43 lying substantially parallel with the member 39. The portion 43 is adapted to be secured to the member 39 by means of low melting point solder shown at 45.

The angular member 41 is provided with a slot 47 through which the connector 31 may pass so as to permit the connector 31 to act as a strain member serving to withstand the longitudinal stress placed upon the contact rod 27 when the refill unit 13 is placed within the fuse device. Although the strain connector 31 is preferably constructed of relatively high resistance material such as "Nichrome," comprising about 78% nickel and 20% chromium, other suitable materials may be used.

When disposed within the fuse casing, the upper edge of the ferrule 17 of the refill unit 13 engages an inwardly projecting shoulder 48 of the lower cap member 9 and is clamped in position by a collar 49 screw threaded into the lower end of the lower cap member 9, which collar in turn engages the lower end of the ferrule 17. The upper and screw threaded end of contact rod 27 is connected to a spring support block 51 to which a tensioning spring 53 is attached at its lower end and which spring is secured at its upper end to the upper terminal cap 1, thereby placing the contact rod 27 and the two fusible connections 29 and 31 under tension. Details of the connections between the refill unit 13 and the upper cap terminal 1 are more clearly set forth in the patent to H. L. Rawlins, No. 1,976,634, issued October 9, 1934.

Insofar as the instant application is concerned, it will be sufficient to state that the upper cap terminal 1 makes electrical connection with the spring support member 51 by means of a flexible shunt 55. Thus, the electrical circuit through the fuse device, as shown in Fig. 1, proceeds from the upper cap terminal 1 through the flexible shunt 55, member 51, conductor rod 27, fusible connections 29 and 31, ferrule 17, and terminates with the lower cap member 9. The contact rod 75

27 is of somewhat smaller diameter than the bore through the lining member 23, so as to permit a predetermined amount of lateral movement within the lining member. The connecting members 39 and 41 when in the joined condition, are so disposed with respect to the strain connector 31 and the contact rod 27 that the latter is maintained adjacent the right side of the bore in the lining member 23, as viewed in Fig. 4.

10 It will thus be apparent that since the strain connector 31 is disposed out of alignment with the contact rod 27 and the biasing spring 53 exerts a force longitudinally of the contact rod 27, there will exist a component of force upon the conductor 39 at right angles to the force tending to move the contact rod 27 through the bore of the lining member 23. When the current through the fuse device exceeds a predetermined value, the conducting members 39 and 41 become 15 heated so as to melt the fusible joint 45 between these members, thereby permitting them to separate and assume the position as shown in Fig. 4, due to the lateral biasing component produced by the biasing spring 53 and the strain connector 31.

20 Upon separation of the members 39 and 41 in the manner aforesaid, current through the device is diverted through the strain member 31, which due to its higher resistance and relatively 25 low current-carrying capacity, fuses to permit the biasing spring 53 to draw the contact rod 27 upwardly through the core of the tubular lining member 23 and to establish an arc therein. The action of the arc upon the side walls of the lining member 23 produces large quantities of gas, which cause the arc to be extinguished by expulsive action, which is well understood in the art.

25 From the foregoing, it is apparent that the arrangement of the fusible connecting members 39, 41 and 31 is such that a small but constant lateral biasing force supplied by the main spring 53 is placed upon the member 39 to cause it to separate from the cooperating member 41. The 30 fact that this biasing force is small and is of constant magnitude throughout the life of the fuse device, makes it possible to select a soldering material for joining the connectors 39 and 41 which will give the most desirable operating 35 characteristic. In other words, the fusible solder joint need not withstand as high a mechanical strain as is in some instances encountered when the members 39 and 41 are constructed of bimetal or of spring material.

40 Although I have shown and described a specific fuse structure, it is to be understood that the same is for the purpose of illustration and that changes and modifications may be made by those skilled in the art without departing from the 45 spirit and scope of the appended claims.

55 I claim as my invention:

1. In a circuit interrupter, a pair of relatively 50 rigid conducting members normally secured together and separable upon the occurrence of predetermined conditions, biasing means for applying a force to move one of said conducting members longitudinally, and means cooperating with said biasing means to cause said biasing means to move said conducting members laterally apart 55 prior to substantial movement of said one member longitudinally, and said conducting members being rigid with respect to the force exerted by said biasing means in a direction to move said conducting members laterally apart.

70 2. In a circuit interrupter, a pair of conduc-

tors, means biasing one of said conductors to move away from the other, two connections joining said conductors, the first connection including two relatively rigid members joined by fusible means and adapted to be separated upon fusion of said fusible means in response to the occurrence of predetermined conditions, the second connection being fusible upon separation of said first connection but having sufficient mechanical strength when unfused to withstand the action of said biasing means and being so disposed with respect to said biasing means and said first connection to cause said biasing means to bias the two members of said first connection laterally apart.

3. In a circuit interrupter, means for establishing an arc including a separable joint embodying separable relatively rigid members, a biasing spring for moving longitudinally one of said members for establishing the arc, and means for relieving said members from longitudinal stress of said biasing spring, said last-named means causing said biasing spring to apply a lateral stress laterally upon said separable joint, biasing it to separate upon the occurrence of predetermined current conditions, and said members being rigid with respect to said lateral stress, whereby said biasing spring and stress-relieving means constitute the sole agency for causing said lateral separation.

4. In a circuit interrupter, a tubular closure at least in part of insulating material, a conducting terminal at each end of said tubular closure, conducting means within said closure for normally establishing an electrical circuit between said terminals, said conducting means including two parts joined by fusible means, biasing means for moving one part of said conducting means in a predetermined direction away from the other part upon melting of said fusible means to draw an arc within said closure, and means entirely outside of the main current paths through said interrupter and cooperating with said biasing means for causing the latter to bias said parts to separate initially in a direction substantially at right angles to said predetermined direction upon the fusion of said fusible means.

5. In a circuit interrupter, a tubular closure at least in part of insulating material, a conducting terminal at each end of said tubular closure, a conducting member connected to one of said terminals, biasing means for moving said conducting member through said tubular closure, fusible means connecting said conducting member to the other of said terminals for normally holding said member against movement by said biasing means, said fusible means comprising two fusible connections, one of said connections including a pair of relatively rigid conducting elements secured together by a fusible joint adapted to be separated upon the occurrence of predetermined current conditions, the other of said connections being fusible upon fusion of said fusible joint but having sufficient mechanical strength when unfused to withstand the action of said biasing means, and being secured to said other terminal at a point laterally of said fusible joint and of the line of action of said biasing means for causing said biasing means to apply a lateral stress upon said joint to separate said conducting elements upon fusion of said fusible joint.

6. In a fuse device, a tubular closure at least

5 partially of insulating material defining an elongated arc passage, a conducting terminal at each end of said closure, conducting means extending through said arc passage for establishing a circuit between said terminals, said conducting means comprising a conducting rod freely movable through said arc passage and connected to one of said terminals, spring means biasing said rod for longitudinal movement through said arc 10 passage, a fusible strain wire for connecting said rod to the other of said terminals at a point offset from the axis of said rod for holding said rod against movement by said spring means, and a pair of relatively stiff conducting elements joined by fusible means and connected in parallel relation with said strain wire, said pair of conducting elements having at least their juncture point disposed laterally of said strain wire to provide a biasing component from said spring means for 15 separating said elements upon fusion of said fusible means, in a direction at an angle from the normal line of action of said spring means upon said conducting rod.

7. In a fuse device, a tubular closure at least 20 partially of insulating material defining an elongated arc passage, a conducting terminal at each end of said closure, conducting means extending through said arc passage for establishing a circuit between said terminals, said conducting means comprising a conducting rod freely movable through said arc passage and connected to one of said terminals, said means biasing said rod for longitudinal movement through said arc passage, said conducting rod having limited lateral 25 movement with respect to said arc passage, a fusible strain member for connecting said rod to the other of said terminals and holding said rod against movement by said spring means, said strain member being connected to said other terminal at a point out of axial alignment with the axis of said arc passage to cause said spring means to bias said rod laterally toward one side of said arc passage, and a pair of conducting elements joined by fusible means and connected in 30 parallel relation with said strain member, said fusible means normally holding said conducting elements in fixed relation with respect to each other to maintain said rod away from said one side of said arc passage, and when fused permitting said conducting elements to separate laterally in response to lateral movement of said conducting rod.

8. In a circuit interrupter, a pair of conducting members, fusible means joining said conducting members, biasing means operative for separating said conducting members upon fusion of said fusible means, said biasing means upon fusion of said fusible means moving at least one of said conducting members in a predetermined direction, means for guiding said one conducting member in said predetermined direction and permitting limited lateral movement thereof, said biasing means in cooperation with said members and fusible means normally maintaining said one member adjacent one side of said guide means, and means cooperating with said biasing means to cause said biasing means to bias said one member toward the opposite side of said guide means, whereby upon separation of said one member, from the other, it is moved laterally by said biasing means prior to movement thereof in said one direction.
